UNITED STATES PATENT OFFICE.

CHARLES H. GRANT, OF NEW YORK, N. Y.

TOY AEROPLANE.

1,313,290.

Specification of Letters Patent. Patented Aug. 19, 1919.

Application filed March 21, 1919. Serial No. 284,161.

To all whom it may concern:

Be it known that I, CHARLES H. GRANT, a citizen of the United States, residing at the city, county, and State of New York, have invented certain new and useful Improvements in Toy Aeroplanes, of which the following is a specification.

My invention relates to improvements in a toy aeroplane having a propeller which is rotated by the torsional force of a twisted rubber band.

The principal objects of the invention are, first, to provide a body which is so constructed that the rubber band is concealed from view but is readily accessible for placement or replacement; second, to provide the body with supports or skids so arranged that the device will rise into flight from a standing position, the rear skid being formed to provide a hook for engaging one end of the rubber band; third, to provide the body with a durable bearing surface for the propeller shaft; and, fourth, to provide flexible and adjustable means for attaching the main supporting plane to the body.

I attain the objects specified, as well as others not specifically enumerated, by means of the device hereinafter described and illustrated in the accompanying drawing, in which,

Fig. 1, is a vertical section taken through the longitudinal center line, and,

Fig. 2 is a bottom plan view of the device with the supporting planes broken away.

Referring to the drawings, 1 indicates the body which is made of papier mâché, balsa, or other suitable light and strong material. The body is made of a single piece of material and is formed with a hollow interior 2 having a long and narrow opening, extending along the bottom through which access is had to the interior. The front end or nose of the body is pointed upward, as shown, so as to bring the axis of rotation 45 of the propeller approximately on the line of the center of resistance of the device.

The device is equipped with a main supporting plane 3, a vertical tail 4, and a horizontal tail 5, of suitable proportion and design so as to permit the device to fly through the air when driven by rotation of the propeller.

The main supporting plane 3 is flexibly and adjustably attached to the body by means of a rubber band 16 which is tightly

wrapped around the plane and the body so as to flexibly bind the parts together. The back of the body, at the place of attachment of the plane, is preferably flattened to provide a flat surface for the plane to rest upon. 60 The front edge of the plane normally abuts against a shoulder 17 formed on the front end of the body. A second shoulder 18, elevated slightly above the shoulder 17, is provided upon which the front edge of the plane may be placed if desired to tilt the plane. This construction permits of adjustment of the position and angularity of the plane and also, because of its flexibility, tends to prevent the plane from being 70 broken in case the device should fall or land sidewise. Furthermore, if desired, the plane may be adjusted laterally with respect to the body so as to cause the device to fly in a circle. 75

The propeller 6 is provided with a shaft 7 which is mounted to rotate in a bearing inserted in a dowel pin 8 secured in the front end of the body. The bearing is made of metal or other suitable hard material so as 80 to provide a durable bearing surface for the shaft.

The inner end of the shaft 7 extends into the hollow space in the interior of the body and terminates in a hook 9, which engages 85 a shackle 10 at one end of the rubber band motor 11, the shackle 12 at the other end of the motor being engaged in the hook-shaped part of the member 13, as seen in Fig. 2.

A metal cap 14 is fitted on the rear tapered end of the body to reinforce the same. The member 13, which is preferably made of a single piece of wire, is fastened in place by being inserted vertically through the end of the body and reinforcing cap and having 95 its upper end upset or riveted to hold it in position. The lower extremity of the member 13 is bent forward into the hollow interior of the body and then backward under the end of the body, as shown in Fig. 2, to give 100 the appearance of a skid and to provide a hook for fastening the rear end of the rubber band motor.

A pair of supporting members or skids 15 are fastened to the front part of the body 105 and project forwardly of the propeller so as to form a guard therefor. The front skids 15 extend downward farther than the rear skid 13 so that, when the toy is placed on a flat surface, it will be inclined upward from 110

the rear end toward the front, and is thus enabled to rise into flight from a standing position.

From the foregoing description taken in connection with the accompanying drawing, it will be seen that I have provided a construction whereby the rubber band motor 11 can be easily assembled in place by merely hooking the shackles 10 and 12 to the hooks 9 and 13 respectively and that when thus assembled it is concealed from view in the interior of the body. It will also be apparent that this construction permits of readily replacing the motor 11 with a new one in case of breakage.

I do not limit myself to the precise construction and arrangement of parts hereinabove set forth, as I am aware that various changes and modifications may be made therein without departing from the scope of the invention as pointed out in the claims.

What I claim is:

1. A toy aeroplane comprising a hollow body open at the bottom, supporting planes, a propeller revolubly mounted in the front end of the body, and a rubber band motor disposed within the body and detachably connected to the propeller, said motor being insertible or removable through the opening in the bottom of the body.

2. A toy aeroplane comprising a hollow body open at the bottom, supporting planes, a propeller, a propeller shaft mounted in a bearing at the front end of the body and terminating at its inner end in a hook, a hook-shaped member secured to rear end of the body and projecting into the interior

thereof, a rubber band disposed within the body and having a shackle at each end, said rubber band being detachably engaged in the hooks and being insertible or removable through the opening in the bottom of the body.

3. A toy aeroplane comprising a hollow body open at the bottom, supporting planes, a propeller revolubly mounted in the front end of the body, a pair of skids attached to the body adjacent the front end and extending below and in front of the propeller to form a guard therefor, a hook-shaped member secured to the rear end of the body and having a portion which projects into the interior of the body, a rubber band motor disposed within the body and detachably secured at its ends to the propeller and the hook-shaped member respectively, said rubber band being insertible or removable through the opening in the bottom of the body.

4. In a toy aeroplane of the character described, the combination of a body having a propeller mounted in its front end, said body having its forward portion slanted upward so as to bring the axis of rotation of the propeller substantially on the line of the center of resistance of the device, and having a stepped shoulder formed on its upper surface, a main supporting plane having its front edge abutting against the shoulder, and a rubber band tightly wrapped around the plane and the body whereby to flexibly and adjustably bind the parts together.

CHARLES H. GRANT.
